Primary Examiner — Kendra Leslie Hamilton(74) *Attorney, Agent, or Firm* — Eric Kelly(57) **CLAIM**

The ornamental design for a leash, as shown and described.

DESCRIPTION

FIG. 1 is a top-front perspective view of a leash, showing my new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof; and,

FIG. 7 is a bottom plan view thereof.

Broken lines in the drawings depict portions of the leash that form no part of the claimed design.

1 Claim, 5 Drawing Sheets(56)
